O. P. GREENSTREET,
WASHING APPARATUS.
APPLICATION FILED JUNE 4, 1921.

1,409,292.

Patented Mar. 14, 1922.

By Watson E. Coleman
Attorney

UNITED STATES PATENT OFFICE.

OLIVER P. GREENSTREET, OF QUAPAW, OKLAHOMA, ASSIGNOR OF ONE-HALF TO F. B. CLARK, OF WEBB CITY, MISSOURI.

WASHING APPARATUS.

1,409,292.

Specification of Letters Patent. Patented Mar. 14, 1922.

Application filed June 4, 1921. Serial No. 475,001.

To all whom it may concern:

- Be it known that I, OLIVER P. GREEN-
5 STREET, a citizen of the United States, re-
siding at Quapaw, in the county of Ottawa
and State of Oklahoma, have invented cer-
tain new and useful Improvements in Wash-
ing Apparatus, of which the following is a
specification, reference being had to the ac-
companying drawings.
- 10 This invention relates to certain improve-
ments in washing apparatus, and it is an
object of the invention to provide a novel
and improved apparatus of this general
character which is adapted to be placed sub-
stantially in submergence within a boiler or
15 other container, and which includes a ro-
tary drum or receptacle in which is posi-
tioned the clothing or other articles to be
cleansed.
- 20 Another object of the invention is to pro-
vide a novel and improved apparatus of this
general character wherein the receptacle or
container is caused to rotate by pressure
created by the proper heating of the wash-
25 ing fluid.

The invention consists in the details of
construction and in the combination and ar-
rangement of the several parts of my im-
30 proved washing apparatus whereby certain
important advantages are attained and the
device rendered simpler, less expensive and
otherwise more convenient and advan-
tageous for use, as will be hereinafter more
fully set forth.

35 The novel features of my invention will
hereinafter be definitely claimed.

In order that my invention may be the
better understood, I will now proceed to de-
40 scribe the same with reference to the accom-
panying drawings, wherein:

45 Figure 1 is a view partly in longitudinal
vertical section and partly in elevation illus-
trating a washing apparatus constructed in
accordance with an embodiment of my in-
vention and in applied position, and

Figure 2 is a transverse sectional view
taken through the device as illustrated in
Figure 1.

50 As disclosed in the accompanying draw-
ings, B denotes a boiler or container of
requisite dimensions and configuration and
in which my improved apparatus is adapt-
ed to be inserted.

55 In the present embodiment of my inven-
tion, my improved washing apparatus com-

prises an elongated member M adapted to
be positioned upon the bottom of the boiler
or container B and which, when applied, has
its marginal portions spaced from the walls
of the boiler or container. The member M
is concavo-convex in cross section and the
marginal portions of the member M are se-
cured to a relatively wide continuous flange
1, the upper edges of said flange terminat-
ing slightly above the high point of the
member M.

Extending upwardly from each end por-
tion of the member M at substantially the
transverse center thereof, is a tube 2, said
tube having its upper end portion inwardly
disposed, as at 3, and preferably integrally
connected. The inwardly disposed portions
3 of the tubes 2 have their bores separated
by an interposed septum or partition 4. The
under walls of the inwardly disposed por-
tions 3 of the tubes 2 are provided at oppo-
site sides of the center thereof with the dis-
charge openings 5.

When my improved apparatus is in ap-
plied position within the boiler B or other
50 container, the member M provides therebe-
low a chamber C and said chamber is di-
vided at substantially its center by a trans-
versely directed plate or partition 6 secured
directly to the member M.

In practice, the apparatus is placed within
the boiler B or other container with the
level of the washing fluid at substantially the
line as indicated in Figure 1, and the cloth-
ing or kindred articles to be cleansed are
placed within the boiler or container B di-
rectly above the member M. The fluid in the
boiler or container B is caused to boil and as
the temperature of the fluid, and particu-
larly in the chamber C, rises the fluid will
95 pass upwardly through the tubes 2 and the
extensions 3 thereof and be discharged
downwardly within the boiler or container
B through the openings 5. This action of
the fluid occurs intermittently and at in-
100 tervals of above five seconds, and this rising
of the fluid through the tubes does not occur
simultaneously in both of the tubes, but only
through one tube 2 at a time and generally
in succession. This action is caused by the
105 partitions 4 and 6.

As the fluid within the boiler or container
B rises in temperature, such rise occurs with
greater rapidity at one side of the partition
6 than at the other so that the fluid within
110

the chamber C at said first side of the partition 6 passes upwardly through a tube 2. During this operation, sufficient time is afforded for the fluid at the opposite side of the partition 6 to rise sufficiently to cause the fluid to pass upwardly of the second tube 2 and to be discharged through the openings 5 in the extension 3 thereof.

It has also been fully demonstrated in practice that a considerable amount of pressure is created within the chamber C and which assures the desired rising of the fluid and as the fluid rises upwardly through the tubes 2, a partial vacuum is created within the chamber C resulting in a suction which causes the water within the boiler or container B to be drawn into the chamber C. This return of the water within the chamber C is facilitated in view of the fact that the pressure within the member M causes the entire apparatus to have vibratory movement in a vertical direction.

The dirt or sediment released from the articles during the washing operation is collected upon the member M and retained by the flange 1 and it also happens that a considerable portion of such dirt and sediment is collected upon the inner or under face of the member M and which is apparently due to the creation of the partial vacuum within the chamber C. This statement is made upon observations during actual practice, and at which time it has been particularly noted that but little of the released dirt or sediment is maintained in suspension in the washing fluid.

The central part 2' is laterally offset and interposed in such portion 2' is a casing 7. Revolving within the casing 7 is a rotor 8, having rotating therefrom from the blades or vanes 9. As the fluid under pressure rises upwardly through a tube 2, the associated rotor 8 is caused to rotate, said rising fluid passing upwardly beyond the rotor 8 and being discharged through the openings 5.

Each of the rotors 8 is fixed to a stub shaft 10 disposed through and rotatably supported by the side walls of the casing 7, and is fixed to an end wall or head 11 of a receptacle or drum R. This receptacle or drum R is of a

type generally employed in connection with a washing apparatus, and is adapted to have positioned therein the clothing or other articles to be cleansed. In operation, the fluid under pressure rising upwardly through the tubes results in an intermittent rotation of the receptacle or drum R with the resultant tumbling of the articles therein, and whereby the washing or cleansing of such articles is materially facilitated.

From the foregoing description it is thought to be obvious that a washing apparatus constructed in accordance with my invention is particularly well adapted for use by reason of the convenience and facility with which it may be assembled and operated, and it will also be obvious that my invention is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. washing apparatus comprising a member adapted to be positioned in the lower portion of a receptacle, said member being of a cross sectional configuration to provide a chamber when the apparatus is applied, upstanding tubes carried by the member and in communication with the chamber, a rotor interposed in each of the tubes, and a drum rotatably supported between the tubes and in driven connection with each of the rotors.

2. A washing apparatus comprising a member adapted to be positioned in the lower portion of a receptacle, said member being of a cross sectional configuration to provide a chamber therebelow when applied, upstanding tubes carried by the member and in communication with the chamber, a tumbler drum positioned between and rotatably supported by the tubes, and means operable from the pressure passing up through the tubes for rotating the drum.

In testimony whereof I hereunto affix my signature.

OLIVER P. GREENSTREET.
